UNITED STATES PATENT OFFICE

109,394

DESIGN FOR A RING

John F. Fessel, Defiance, Ohio

Application March 16, 1938, Serial No. 75,876

Term of patent 7 years

To all whom it may concern:

Be it known that I, John F. Fessel, a citizen of the United States of America, residing at Defiance, in the county of Defiance and State of Ohio, have invented a new, original, and ornamental Design for a Ring, of which the following is a specification, reference being had to the accompanying drawing, forming a part thereof.

In the drawing:

I claim:

The ornamental design for a ring, as shown.

JOHN F. FESSEL.
